Wilmette, Ill., assignors to General Electric Company, a corporation of New York

Filed Nov. 9, 1964, Ser. No. 82,527

Term of patent 14 years

(Cl. D59—2)

FIG. 1 is a front elevational view of a jacket for a record and related picture slide showing my new design in closed position, the back thereof being substantially similar thereto;

FIG. 2 is a top plan view thereof;

FIG. 3 is a perspective view thereof as it appears in an open position, the broken line showing of a record being for purposes of illustration only; and

FIG. 4 is a perspective view of another embodiment of the inside of the design shown in FIG. 1, the broken line showing of a record being for purposes of illustration only.

The essential features of our design reside in the full line disclosure on the drawing.

We claim:

The ornamental design for a jacket for a record and related picture slide, substantially as shown and described.
